UNITED STATES PATENT OFFICE.

CHARLES L. FOWLE, OF DOWAGIAC, MICHIGAN, ASSIGNOR TO DOWAGIAC MANUFACTURING COMPANY, OF DOWAGIAC, MICHIGAN.

MULTIPLE EVENER.

SPECIFICATION forming part of Letters Patent No. 759,361, dated May 10, 1904.

Application filed January 18, 1904. Serial No. 189,588. (No model.)

To all whom it may concern:

Be it known that I, CHARLES L. FOWLE, a citizen of the United States, residing at the city of Dowagiac, in the county of Cass and State 5 of Michigan, have invented certain new and useful Improvements in Multiple Eveners, of which the following is a specification.

This invention relates to improvements in multiple eveners.

10 It relates to three and four horse eveners and to any number of eveners for more than two horses. It is especially adapted for use on grain-drills, although the same can of course be made use of on other machines of similar 15 draft construction, particularly those having two poles, such as large field-cultivators and the like.

A serious difficulty with three and four horse eveners as heretofore constructed has been to 20 secure them in substantially a level position and yet permit all of the freedom of movement necessary to secure the desired equalizing action.

This invention has to do with providing im- 25 proved means of properly supporting in position a three and four horse evener, so that its movement is considerably restricted without in any way interfering with its efficiency and with its weight suspended intermediate its coupling 30 to the machine and harness-coupling to the eveners and having sufficient clevis action to allow the eveners to swing freely into line of of draft with the tugs of the harness, thereby causing a straight line of draft from the harness-hames to the coupling of eveners with the machine.

Objects relating to the details of construction will fully appear from the detailed description to follow.

40 I accomplish the objects of my invention by the devices and means described in the following specification.

The invention is clearly defined, and pointed out in the claims.

45 A structure embodying the features of my invention as applied to a four-horse evener is clearly illustrated in the accompanying drawings, forming a part of this specification, in which—

Figure 1 is a detail view of the improved 50 evener in its proper relation to the framework and tongues of a grain-drill, portions of the timbers being broken away. Fig. 2 is a detail sectional elevation view taken on line 2 2 of Fig. 1. Fig. 3 is an enlarged detail sectional view of the main clevis taken on line 3 3 of Fig. 1. Fig. 4 is an enlarged detail sectional view taken on a line corresponding to lines 4 4 of Figs. 1 and 2.

In the drawings the sectional views are taken 60 looking in the direction of the little arrows at the ends of the section lines, and similar letters of reference refer to similar parts throughout the several views.

Referring to the lettered parts of the drawings, the frame is of the usual or any desired construction and is here illustrated as having front and rear pieces A A, which are secured together by tongues A' A', the front portion of the tongues being broken away. A draw- 70 bar B of any desired construction connects to the frame and extends forwardly between the two tongues A' A' and is connected by the usual or any suitable clevis B" to the main evener B'. This main bar is connected by a 75 suitable clevis or suitable pivotal connections to a pair of doubletrees of any usual construction at each end, the doubletree-bar C C being connected by suitable pivots to the swingletrees c c at each end.

80 The pivoted bolt a", which connects the main evener-bar to the doubletree, is provided with an eye at its upper end, to which is connected the supporting-chain a'. The upper end of the supporting-chain is secured to an 85 elongated rod-loop a, the main body of which is slightly inclined so as to allow the evener to drop down a little as it is swung back. This rod a extends through the upper link of the supporting-chain a'. This, it will be 90 seen, allows a complete freedom of movement back and forth of the main evener-bar B', and yet properly supports within the limited range of movement up and down the doubletrees at each end of this main evener-bar. Owing to 95 the fact that the loop a is elongated, the movement back and forth is amply provided for. By this means the evener is as effective as it

would be if left entirely free at each end, and at the same time its movements are entirely confined within any desired limit, the desirability of which is obvious when the necessary 5 size and length of these devices is taken into consideration.

Any link connection between the doubletrees and the loop *a* would serve the purpose, although the chain is obviously the best and 10 most convenient.

Details of this structure can obviously be modified indefinitely within the range of art of improvements in whiffletrees, the details of the construction of the evener itself, aside 15 from the supporting means, being immaterial.

Having thus described my invention, what I claim as new, and desire to secure by Letters Patent, is—

20 1. In a multiple evener, the combination of a frame; a draw-bar connected to the frame; a main evener-bar connected by a suitable clevis to the draw-bar, doubletrees at each end of the evener-bar; the pivot-bolts of which are 25 provided with eyes at their upper ends; poles *A' A'* extending above the ends of the main evener-bar with an elongated rearwardly-inclined loop *a* on the under side, and a chain *a'* connected to the eye on the doubletree-bolt 30 and to the loop *a* so that it is freely movable along the same, coacting for the purpose specified.

2. In a multiple evener, the combination of a frame; a main evener-bar connected by a 35 suitable clevis; doubletrees at each end of the evener-bar, the pivotal bolts of which are provided with eyes at their upper ends; poles *A' A'* extending above the ends of the main evener-bar with an elongated rearwardly-in- 40 clined loop *a* on the under side, and a chain *a'* connected to the eye on the doubletree-bolt and to the loop *a* so that it is freely movable along the same, coacting for the purpose specified.

45 3. In a multiple evener, the combination of a frame; a main evener-bar connected by a suitable clevis; doubletrees at each end of the evener-bar, the pivot-bolts of which are provided with eyes at their upper ends; poles *A' A'* extending above the ends of the main 50 evener-bar with elongated loop *a* on the un-

der side, and a chain *a'* connected to the eye on the doubletree and to the loop *a* so that it is freely movable along the same, coacting for the purpose specified.

55

4. In a multiple evener, the combination of a frame; a main evener-bar connected by a suitable clevis; doubletrees at each end of the evener-bar; poles *A' A'* extending above the ends of the main evener-bar with an elongated loop *a* on the under side, and a chain *a'* connected to the doubletree and to the loop *a* so that it is freely movable along the same, coacting for the purpose specified.

60

5. In a multiple evener, the combination of a frame; a main evener-bar connected by a suitable clevis to the frame; doubletrees at each end thereof; longitudinal loops connected to the frame above the doubletrees; a chain connecting the doubletrees and the end of the main evener-bar to the loop so that the same 65 may play freely backward and forward, for the purpose specified.

65

6. In a multiple evener, the combination of a frame; a main evener-bar connected by a suitable clevis to the frame; doubletrees at each end thereof; longitudinal loops connected to the frame above the doubletrees; and a connection for the doubletrees and the end of the main evener-bar to the loop so that the same 70 may play freely backward and forward, for the purpose specified.

70

7. In an evener, the frame; a main evener-bar connected by a suitable clevis to the frame; longitudinal loops secured to the frame above each end of the evener; and a chain connecting the ends of the evener-bar to the loop so that the same may play freely backward and forward, for the purpose specified.

75

8. In an evener, the frame; a main evener-bar connected by a suitable clevis to the frame; longitudinal loops secured to the frame above each end of the evener; and a connection for the ends of the main evener-bar to the loop so that the same may play freely backward and 80 forward, for the purpose specified.

80

In witness whereof I have hereunto set my hand and seal in the presence of two witnesses.

CHARLES L. FOWLE. [L. s.]
